UNITED STATES PATENT OFFICE.

ARTHUR B. CLUNIES, OF ROCHESTER, NEW YORK, ASSIGNOR TO THE SILL STOVE WORKS, OF SAME PLACE.

DESIGN FOR A FIRE-POT LINING.

SPECIFICATION forming part of Design No. 25,888, dated August 4, 1896.

Application filed June 18, 1896. Serial No. 596,081. Term of patent 14 years.

To all whom it may concern:

Be it known that I, ARTHUR B. CLUNIES, a citizen of the United States, residing at Rochester, in the county of Monroe and State of New York, have invented and produced a new and original Design for a Fire-Pot Lining for Stoves and Ranges, of which the following is a specification, reference being had to the accompanying drawings thereof.

10 Figure 1 is a perspective view of the front of my design for fire-pot lining; Fig. 2, a rear elevation of the same.

The leading feature of my design is the shape and configuration of the fire-pot lining.

15 1 indicates the top of the lining, and 2 the face thereof, extending at substantially right angles thereto. The face 2 is curved slightly outward at 3 to meet the surface 4, near one end curved down to the thin edge, and at the

20 upper part of the curved surface 4 is a recess 5, a corresponding projection 6 being formed on the rear side of the lining, as at the left of Fig. 2. The extreme end (at the right in Fig. 1) is provided with the recess 7, the lower

25 part of which is cut through the web, and at

the extreme lower portion of this end is provided with the flange 8. On the rear side this end is provided with a rearward projection 9.

The left end, Fig. 1, of the lining is slightly rounding on the face, and at the upper end is a recess 10, corresponding to the projection 11 on the rear, and the lower part of the face has the flange 12 and is cut away at 13 beneath it. The extreme left edge, Fig. 1, is recessed or notched at 14. The rear of this left end is shown particularly in Fig. 2 at the right, being curved and shaped the reverse of the front side and provided with the rearwardly-extending projection 15, corresponding generally to the projection 9 on the other end.

What I claim is—

The design for a fire-pot lining substantially as herein shown and described.

ARTHUR B. CLUNIES.
